CLAIM

The ornamental design for a shoe, as shown and described.

DESCRIPTION

FIG. 1 is a side view of a shoe showing my new design; and, FIG. 2 is a rear perspective view thereof.

The broken lines immediately adjacent to the photographic area define the bounds of the claimed design and form no part thereof. The broken lines showing of the three circle shaped elements represent eyelets that form no part of the claimed design. The broken lines depicting the remainder of the shoe form no part of the claimed design.
